(57) **ABSTRACT**

There is provided a liquid discharge head including a first channel unit and a second channel unit. The first channel unit includes: a first joining surface; a tube disposed on an opposite surface opposite to the first joining surface; an outside portion; and a coupling portion. The second channel unit is joined to the first joining surface. An end of the outside portion and an end of the coupling portion in an orthogonal direction orthogonal to the first joining surface extend to an identical position in the orthogonal direction. The tube includes a circumferential portion that is exposed outside and extends in the orthogonal direction to the identical position to which the end of the outside portion and the end of the coupling portion extend.

LIQUID DISCHARGE HEAD

CROSS REFERENCE TO RELATED APPLICATION

The present application claims priority from Japanese Patent Application No. 2018-181402 filed on Sep. 27, 2018, the disclosure of which is incorporated herein by reference in its entirety.

BACKGROUND

Field of the Invention

The present disclosure relates to a liquid discharge head including a first channel unit and a second channel unit that are joined to each other.

Description of the Related Art

There is known a technique in which two units included in a liquid discharge head and respectively having channels are joined to each other. For example, there is known a technique in which a channel unit (a second channel unit) including a channel formed having a nozzle and a pressure chamber is joined to a casing (a first channel unit) that is made using a resin and includes a channel for introducing ink from the outside into the channel unit. A joining surface of the casing on the opposite side of the surface to which the channel unit is joined is provided with a tube defining an ink introduction opening, a raised portion defining a gap, and a rib coupling the tube with the raised portion.

SUMMARY

In the above liquid discharge head, the rib does not protrude beyond the tube and the joining surface. This makes it difficult to press the rib when the casing (the first channel unit) is joined to the channel unit (the second channel unit). The shortage of pressing force may cause joining failure.

An object of the present disclosure is to provide a liquid discharge head that inhibits joining failure between a first channel unit and a second channel unit.

According to an aspect of the present disclosure, there is provided a liquid discharge head, including: a first channel unit in which a first channel is defined, the first channel unit including: a first joining surface; an opposite surface that is opposite to the first joining surface; a tube disposed on the opposite surface and defining the first channel; an outside portion disposed on the opposite surface and positioned outside the tube; and a coupling portion disposed on the opposite surface and coupling the outside portion and the tube, and a second channel unit in which a second channel communicating with the first channel is defined, the second channel unit including a second joining surface joined to the first joining surface of the first channel unit. An end of the outside portion and an end of the coupling portion in an orthogonal direction orthogonal to the first joining surface extend to an identical position in the orthogonal direction. The tube includes a circumferential portion that is exposed outside and extends in the orthogonal direction to the identical position to which the end of the outside portion and the end of the coupling portion extend.

BRIEF DESCRIPTION OF THE DRAWINGS

FIG. 1 is a plan view of a printer 100 including heads 1. FIG. 2 is a perspective view of the head 1.

2

FIG. 3 is a plan view of a channel unit 20z included in a second channel unit 20 of the head 1.

FIG. 4 is a cross-sectional view of the second channel unit 20 taken along a line IV-IV in FIG. 3.

5 FIG. 5 is a plan view of a joint unit 20x included in the second channel unit 20 of the head 1.

FIG. 6 is a plan view of a first channel unit 10 of the head 1.

FIG. 7 is a cross-sectional view of the first channel unit 10 10 and the joint unit 20x taken along a line VII-VII in FIG. 6.

FIG. 8 is a perspective view of a lower surface 10b of the first channel unit 10.

15 FIG. 9A is a plan view of a channel unit 20z1, FIG. 9B is a plan view of a channel unit 20z2, and FIG. 9C is a plan view of a channel unit 20z3.

DESCRIPTION OF THE EMBODIMENTS

<Printer 100>

20 Referring to FIG. 1, a configuration of a printer 100 including heads 1 according to an embodiment of the present disclosure is explained. A sheet width direction, a conveyance direction, and a vertical direction in this embodiment are defined as indicated in FIG. 1.

25 The printer 100 includes a head unit 2 provided with four head units 1, a platen 3, a conveyer 4, and a controller 5.

The conveyer 4 has two roller pairs 4a, 4b. The two roller pairs 4a, 4b are arranged such that the platen 3 is interposed between the roller pair 4a and the roller pair 4b in the 30 conveyance direction (a direction orthogonal to the vertical direction). When a conveyance motor (not depicted) is driven, the roller pairs 4a, 4b nipping a sheet 9 are rotated to convey the sheet 9 in the conveyance direction.

The head unit 2 is a line-type head unit in which ink is 35 discharged from nozzles 33d (see FIGS. 3 and 4) on the sheet 9 with the position of the head unit 2 being secured. The head unit 2 is elongated in the sheet width direction, which is orthogonal to the vertical direction and the conveyance direction. The four heads 1 are arranged zigzag in the sheet width direction.

The platen 3, which is a flat-plate member, is disposed 40 below the head unit 2 in a position between the two roller pairs 4a, 4b in the conveyance direction. The sheet 9 is placed on an upper surface of the platen 3.

45 The controller 5 includes a Read Only Memory (ROM), a Random Access Memory (RAM), and an Application Specific Integrated Circuit (ASIC). The ASIC executes a recording process and the like in accordance with programs stored in the ROM. In the recording process, the controller 50 5 controls the conveyance motor (not depicted) and a driver IC 60 (see FIG. 7) of each head 1 to record an image on the sheet 9 based on a recording command (including image data) input from an external apparatus, such as a PC.

<Head 1>

55 As depicted in FIG. 2, the head 1 includes a first channel unit 10 and a second channel unit 20 disposed on the lower side of the first channel unit 10. The first channel unit 10 and the second channel unit 20 are stacked on top of each other in the vertical direction. The first channel unit 10 is joined 60 to the second channel unit 20. Each of the first channel unit 10 and the second channel unit 20 has a substantially rectangular parallelepiped shape that is long in the sheet width direction.

<Second Channel Unit 20>

65 The second channel unit 20 has a joint unit 20x, a filter unit 20y disposed on the lower side of the joint unit 20x, and a channel unit 20z disposed on the lower side of the filter unit

20y. The units 20x, 20y, and 20z are stacked on top of each other in the vertical direction. The units 20x, 20y, and 20z are joined to each other.

As depicted in FIG. 4, the channel unit 20z includes five plates 21 to 25. The five plates 21 to 25 are stacked on top of each other in the vertical direction. The five plates 21 to 25 are joined to each other.

Of the five plates 21 to 25, the lowermost plate 25 has through holes forming the respective nozzles 33d.

The plate 24 is disposed on an upper surface of the plate 25. The plate 24 has through holes forming respective pressure chambers 33c. Each of the pressure chambers 33c corresponds to one of the nozzles 33d. As depicted in FIG. 3, the nozzle 33d overlaps in the vertical direction with a center portion of the pressure chamber 33c in the sheet width direction and the conveyance direction.

Four rows R1 to R4 are arranged side by side in the conveyance direction. Each of the four rows R1 to R4 is extended in the sheet width direction, and includes a plurality of pairs of the nozzle and the pressure chamber. Each of the pairs of the nozzle and the pressure chamber includes one nozzle 33d and one pressure chamber 33c. A black ink is discharged from the nozzles 33d belonging to the first row R1 from an upstream side in the conveyance direction. A yellow ink is discharged from the nozzles 33d belonging to the second row R2 from the upstream side in the conveyance direction. A cyan ink is discharged from the nozzles 33d belonging to the third row R3 from the upstream side in the conveyance direction. A magenta ink is discharged from the nozzles 33d belonging to the fourth row R4 from the upstream side in the conveyance direction.

As depicted in FIG. 4, a vibration film 26 is disposed on an upper surface of the plate 24. The vibration film 26 covers the pressure chambers 33c. The vibration film 26 has through holes forming inflow channels 33b at portions overlapping in the vertical direction with downstream ends in the conveyance direction of the pressure chambers 33c belonging to the rows R1 and R2 (see FIG. 3) and at portions overlapping in the vertical direction with upstream ends in the conveyance direction of the pressure chambers 33c belonging to the rows R3 and R4 (see FIG. 3). Further, the vibration film 26 has through holes forming outflow channels 33e at portions overlapping in the vertical direction with upstream ends in the conveyance direction of the pressure chambers 33c belonging to the rows R1 and R2 (see FIG. 3) and at portions overlapping in the vertical direction with downstream ends in the conveyance direction of the pressure chambers 33c belonging to the rows R3 and R4 (see FIG. 3). The vibration film 26 is made using, for example, silicon dioxide (SiO_2). In that case, the vibration film 26 can be formed by oxidizing the upper surface of the plate 24.

The plate 23 is disposed on an upper surface of the vibration film 26. As depicted in FIGS. 3 and 4, the plate 23 has through holes forming inflow channels 33a at portions overlapping in the vertical direction with the respective inflow channels 33b and through holes forming outflow channels 33f at portions overlapping in the vertical direction with the respective outflow channels 33e. As depicted in FIG. 4, a lower surface of the plate 23 includes four recesses 23x that accommodate respective actuators 40. Each of the actuators 40 is disposed in a space formed by the vibration film 26 and the recess 23x.

The actuators 40 correspond to the respective four rows R1 to R4. Each actuator 40 includes a common electrode 42 disposed on the upper surface of the vibration film 26, a piezoelectric body 41 disposed on an upper surface of the common electrode 42, and individual electrodes 43 disposed

on an upper surface of the piezoelectric body 41. The piezoelectric body 41 and the common electrode 42 extend in the sheet width direction over the pressure chambers 33c belonging to each of the rows R1 to R4. The individual electrodes 43 are provided corresponding to the pressure chambers 33c to overlap in the vertical direction the respective pressure chambers 33c.

The common electrode 42 and the individual electrodes 43 are connected to a Chip On Film (COF) 50. The common electrode 42 and the individual electrodes 43 are electrically connected to the driver IC 60 (see FIG. 7) via the COF 50. The controller 5 controls the driver IC 60 to keep the potential of the common electrode 42 the ground potential and to change the potential of each individual electrode 43. Specifically, the driver IC 60 generates a driving signal based on a control signal from the controller 5 and supplies the driving signal to the individual electrode 43. This changes the potential of the individual electrode 43 between a predefined driving electrode and the ground potential. The change in potential of the individual electrode 43 deforms a portion that is included in the vibration film 26 and the piezoelectric body 41 and is interposed between the individual electrode 43 and the pressure chamber 33c so that the portion becomes convex toward the pressure chamber 33c. This changes the volume of the pressure chamber 33c to apply pressure to ink in the pressure chamber 33c, thus discharging ink from the nozzle 33d.

The individual channels 33 are formed in the plates 23 to 25 and the vibration film 26. Each of the individual channels 33 includes the inflow channel 33a, the inflow channel 33b, the pressure chamber 33c, the nozzle 33d, the outflow channel 33e, and the outflow channel 33f.

The plate 22 is disposed on an upper surface of the plate 23. The plate 22 includes four supply common channels 31e and four return common channels 32e. As depicted in FIG. 3, a set or group of one supply common channel 31e and one return common channel 32e is provided for each of the four rows R1 to R4. The arrangement of the common channels 31e and 32e in the rows R1 and R2 is opposite to that in the rows R3 and R4. The return common channel 32e is disposed at the upstream side in the conveyance direction and the supply common channel 31e is disposed at the downstream side in the conveyance direction in each of the rows R1 and R2, and the supply common channel 31e is disposed at the upstream side in the conveyance direction and the return common channel 32e is disposed at the downstream side in the conveyance direction in each of the rows R3 and R4. The supply common channels 31e extend in the sheet width direction to overlap in the vertical direction with the inflow channels 33a that communicate with the pressure chambers 33c belonging to the rows R1 to R4. The return common channels 32e extend in the sheet width direction to overlap in the vertical direction with the outflow channels 33f that communicate with the pressure chambers 33c belonging to the rows R1 to R4.

As depicted in FIG. 4, the plate 21 is disposed on an upper surface of the plate 22. As depicted in FIG. 3, the plate 21 has supply holes 31ex at portions overlapping in the vertical direction with ends in the sheet width direction of each supply common channel 31e and return holes 32ex at portions overlapping in the vertical direction with ends in the sheet width direction of each return common channel 32e.

As depicted in FIG. 4, the filter unit 20y includes three plates 27 to 29. The plate 29 is disposed on an upper surface of the plate 21. The plate 28 is disposed on an upper surface of the plate 29. The plate 27 is disposed on an upper surface

of the plate 28. The three plates 27 to 29 are stacked on top of each other in the vertical direction. The three plates 27 to 29 are joined to each other.

The joint unit 20x is a member having a rectangular parallelepiped shape and made using a resin (e.g., liquid crystal polymer resin and epoxy resin). The joint unit 20x is disposed on an upper surface of the plate 27.

The filter unit 20y and the joint unit 20x are formed having channels 31a to 31d communicating with the supply common channels 31e via the supply holes 31ex (see FIG. 3) and channels 32a to 32d communicating with the return common channels 32e via the return holes 32ex (see FIG. 3). The channels 31a to 31e form a supply channel 31 and the channels 32a to 32e form a return channel 32. In the plate 28, through holes forming the channels 31c and 32c are provided with respective filters F1 and F2.

As depicted in FIG. 5, an upper surface of the joint unit 20x (an upper surface 20a of the second channel unit 20) has four circular openings 21a, four circular openings 21b, and four circular openings 21d, four openings 21c extending in the sheet width direction and arranged in the conveyance direction, and a wall 20w defining those openings. Two of the four openings 21a, two of the four openings 21b, and two of the four openings 21d are disposed at one end in the sheet width direction of the upper surface 20a, and the remaining two openings 21a, the remaining two openings 21b, and the remaining openings 21d are disposed at the other end. The four openings 21c are provided at a center portion in the sheet width direction of the upper surface 20a. A set or group of one opening 21a, one opening 21b, one opening 21c, and one opening 21d is provided for each of the four rows R1 to R4.

The opening 21a and opening 21b communicate with the channel 31a (see FIG. 4). The joint unit 20x includes a channel extending from the channel 31b to the opening 21a via the channel 31a and a channel extending from the channel 31b to the opening 21b. The channel extending from the channel 31b to the opening 21a via the channel 31a forms the supply channel 31. The channel extending from the channel 31b to the opening 21b forms a supply branch channel branching off from the supply channel 31.

The opening 21c and opening 21d communicate with the channel 32d (see FIG. 4). The opening 21c is provided at an upper end of the channel 32a. The joint unit 20x includes a channel branching off from the channel 32d and extending to the opening 21d without passing through the filter F2. The channel forms a return branch channel branching off from the return channel 32.

As depicted in FIG. 5, the upper surface 20a has positioning holes 1Q at ends in the sheet width direction.

<First Channel Unit 10>

The first channel unit 10 is integrally molded by using a resin (e.g., liquid crystal polymer resin and epoxy resin). As depicted in FIG. 6, the first channel unit 10 has positioning holes 1P at the ends in the sheet width direction. The positioning holes 1P are formed at positions overlapping in the vertical direction with the positioning holes 1Q (see FIG. 5). The positioning holes 1P pass through the first channel unit 10 in the vertical direction.

As depicted in FIG. 7, the first channel unit 10 has a lower surface 10b joined to the upper surface 20a of the second channel unit 20 and an upper surface 10a disposed on the opposite side of the lower surface 10b.

As depicted in FIGS. 2, 6, and 7, the upper surface 10a includes tubes 11, an outside portion 14 having a rectangular frame shape and positioned outside the upper surface 10a with respect to the tubes 11, and a coupling portion 16

coupling the outside portion 14 and the tubes 11. Each tube 11 has a substantially columnar shape extending in the vertical direction. The outside portion 14 includes a pair of walls 14x extending in the sheet width direction and the vertical direction and a pair of walls 14y extending in the conveyance direction and the vertical direction. The coupling portion 16 includes three walls 16x extending in the sheet width direction and the vertical direction and six walls 16y extending in the conveyance direction and the vertical direction. The length (height) in the vertical direction of the walls 14x, 16x is longer than the length (thickness) in the conveyance direction of the walls 14x, 16x. The length (height) in the vertical direction of the walls 14y, 16y is longer than the length (thickness) in the sheet width direction of the walls 14y, 16y. For example, the length (height) in the vertical direction of the walls 14x, 14y, 16x, and 16y may be approximately 10 mm, the length (thickness) in the conveyance direction of the walls 14x, 16x and the length (thickness) in the sheet width direction of the walls 14y, 16y may be approximately 0.8 mm.

Upper ends in the vertical direction of the outside portion 14 and the coupling portion 16 have the same height. Each tube 11 includes a base 11x, a protrusion 11y, and a circumferential portion 11z. The base 11x of the tube 11 is disposed in the same range in the vertical direction as the outside portion 14 and the coupling portion 16 (in other words, overlapping in the sheet width direction or the conveyance direction with the outside portion 14 and the coupling portion 16). The protrusion 11y of the tube 11 is positioned above the base 11x. The circumferential portion 11z of the tube 11 is a boundary between the base 11x and the protrusion 11y and has the same height in the vertical direction as the upper ends of the outside portion 14 and the coupling portion 16. The circumferential portion 11z and the upper ends of the outside portion 14 and the coupling portion 16 are exposed to the outside.

Each tube 11 defines a channel 11m passing through the first channel unit 10 in the vertical direction. The tubes 11 include four tubes 11a overlapping in the vertical direction with the four openings 21a (see FIG. 5), four tubes 11b overlapping in the vertical direction with the four openings 21b (see FIG. 5), four tubes 11c overlapping in the vertical direction with center portions in the sheet width direction of the four openings 21c (see FIG. 5), and four tubes 11d overlapping in the vertical direction with the four openings 21d (see FIG. 5). As depicted in FIG. 6, a set or group of one tube 11a, one tube 11b, one tube 11c, and one tube 11d is provided for each of the four rows R1 to R4. A total of 16 tubes 11 are arranged symmetrically with respect to a center point O of the first channel unit 10 in a plane orthogonal to the vertical direction. The six tubes 11 and the coupling portion 16 are arranged at each end in the sheet width direction of the first channel unit 10. The four tubes 11c and the coupling portion 16 are arranged at a center portion in the sheet width direction of the first channel unit 10.

As depicted in FIGS. 7 and 8, the lower surface 10b has openings 11mx of the channels 11m of the tubes 11, openings 12x of four channels 12 overlapping in the vertical direction with the four openings 21c, the positioning holes 1P, and a wall 10w defining the openings. The openings 12x of the four channels 12 extend in the sheet width direction and are arranged in the conveyance direction. As depicted in FIG. 8, the openings 11mx of the channels 11m of the four tubes 11c are provided at bottom surfaces of the four openings 12x.

As depicted in FIG. 7, the four channels 12 communicate with the four channels 32a via the openings 12x and openings 21c. Of the four channels 12, the first and fourth

channels **12** from the upstream side in the conveyance direction are defined by lower ends of the walls **14x** of the outside portion **14** and lower ends of the walls **16x** of the coupling portion **16**, and the second and third channels **12** from the upstream side in the conveyance direction are defined by lower ends of the walls **16x** of the coupling portion **16**. The walls **14x**, **16x** do not overlap in the vertical direction with the openings **21c** and overlap in the vertical direction with portions included in the wall **20w** and extending in the sheet width direction to define the openings **21c**.

Portions (lower ends of the three walls **16x**) included in the wall **10w** and positioned between the channels **12** in the conveyance direction each have a length **L1** in the conveyance direction. Portions included in the wall **20w** and positioned between the channels **32a** in the conveyance direction each have a length **L2** in the conveyance direction. In order to overlap the wall **10w** with the wall **20w** in the vertical direction even when the positional displacement of the first channel unit **10** to the second channel unit **20** in the conveyance direction is caused during the joining, the length **L2** is longer than the length **L1**. The length **L2** can be longer than the length **L1** by not less than 0.5 mm. For example, the length **L2** may be 1.5 mm and the length **L1** may be 0.8 mm. A center-to-center distance **D** in the conveyance direction between the four openings **12x** is the same as a center-to-center distance **D** in the conveyance direction between the four openings **21c**.

As depicted in FIG. 8, areas of the wall **10w** on both sides in the sheet width direction with the four openings **12x** interposed therebetween overlap in the vertical direction with the wall **20w** (see FIG. 5). In the above areas, the openings **11mx** of the tubes **11a**, **11b**, and **11d** overlap in the vertical direction with the openings **21a**, **21b**, and **21d**.

The above areas of the wall **10w** have recesses **19** between the openings **11mx**. Each recess **19** is separated from each opening **11mx** by not less than 0.5 mm. The recess(es) **19** is/are formed between the openings **11mx**. Further, the recess(es) **19** is/are formed at the outside of the openings **11mx**.

As depicted in FIG. 6, the outside portion **14** has four corners **14p1** to **14p4** protruding outward. The corner **14p1** is different in shape from the remaining corners **14p2** to **14p4**. Specifically, the corner **14p1** includes a notch or cutout larger than those of the corners **14p2** to **14p4**. Similar to this configuration, as depicted in FIG. 5, the joint unit **20x** includes four corners **20p1** to **20p4** protruding outward. The corner **20p1** is different in shape from the remaining corners **20p2** to **20p4**. Specifically, the corner **20p1** includes a notch or cutout larger than those of the corners **20p2** to **20p4**. The corners **14p1** and **20p1** have the same shape when seen in the vertical direction.

As depicted in FIGS. 6 and 7, outside surfaces of the walls **14x** of the outside portion **14** have hollows **14t** for guiding the COF **50**. The COF **50** has a first end connected to the actuators **40** (see FIG. 4) and a second end connected to a control board (not depicted) disposed above the first channel unit **10**. A portion, of the COF **50**, between the first end and the second end is pulled out toward the outside of the second channel unit **20** in the sheet width direction and extending upward and toward the outside of the first channel unit **10**. As depicted in FIG. 7, the driver IC **60** is placed on an outer surface of the COF **50**. A heatsink **70** is installed in the outside portion **14** to cover the driver IC **60**. The heatsink **70**, which is made using a material enabling heat release, is brought into contact with and thermally connected to the driver IC **60**. The material enabling heat release is a material having high thermal conductivity. For example, it is possible

to use a metal material such as aluminum. An urging member **65** such as a sponge is disposed at a portion of an inner surface of the COF **50** (a surface opposite to the surface on which the driver IC **60** is placed) overlapping in the sheet width direction with the driver IC **60**. The urging force of the urging member **65** directed from the inside toward the outside results in a reliable contact between the driver IC **60** and the heatsink **70**.

<Circulation of Ink>

10 Each tube **11** communicates with a subtank (not depicted) corresponding thereto via a tube attached to the protrusion **11y**. The subtanks correspond to the respective rows **R1** to **R4** and contain inks of the respective colors. The four tubes **11** belonging to the row **R1** communicate with the subtank containing the black ink, the four tubes **11** belonging to the row **R2** communicate with the subtank containing the yellow ink, the four tubes **11** belonging to the row **R3** communicate with the subtank containing the cyan ink, and the four tubes **11** belonging to the row **R4** communicate with the subtank containing the magenta ink.

15 Four main tanks (not depicted) respectively containing the black ink, yellow ink, cyan ink, and magenta ink are installed in the printer **100**. The subtank provided for the row **R1** communicates with the main tank for the black ink and contains the black ink supplied from the corresponding main tank. The subtank provided for the row **R2** communicates with the main tank for the yellow ink and contains the yellow ink supplied from the corresponding main tank. The subtank provided for the row **R3** communicates with the main tank for the cyan ink and contains the cyan ink supplied from the corresponding main tank. The subtank provided for the row **R4** communicates with the main tank for the magenta ink and contains the magenta ink supplied from the corresponding main tank.

20 For example, in the recording process, the controller **5** circulates ink along a circulation route starting from and returning to the subtank via the supply channel **31**, each individual channel **33**, and the return channel **32**. Ink in the subtank passes through the channel **11m** in the tube **11a** and is supplied to the supply channel **31** (see FIG. 4) through the opening **21a** (see FIG. 5). The ink passes through the channels **31a** to **31d**, flows into the supply common channel **31e** through the supply holes **31ex** (see FIG. 3), and then flows into each individual channel **33**. As indicated by arrows in FIG. 4, in each individual channel **33**, ink inflowing from an inlet **33x** (an upper end of the inflow channel **33a**) flows into the pressure chamber **33c** through the inflow channels **33a** and **33b**. Part of the ink in the pressure chamber **33c** is discharged from the nozzle **33d**, and the remaining ink in the pressure chamber **33c** passes through the outflow channels **33e** and **33f** and then outflows through an outlet **33y** (an upper end of the outflow channel **33f**). Ink outflowing through each individual channel **33** passes through the return common channel **32e** and flows into the channels **32d**, **32c**, **32b**, and **32a** (see FIG. 4) through the return holes **32ex** (see FIG. 3). The ink flowing into the channels **32d**, **32c**, **32b**, and **32a** outflows through the opening **21c** (see FIG. 5), passes through the channel **11m** in the tube **11c**, and then returns to the subtank. Circulating ink as described above allows bubbles in each individual channel **33** to be discharged and inhibits the increase in viscosity of ink. When ink contains a settling component (a component that may settle, such as pigment), the component is agitated or stirred to inhibit the settling.

25 30 35 40 45 50 55 60 65 60 In order to remove bubbles accumulating in a lower portion of the filter **F2** at the time of the maintenance of the head **1**, the controller **5** circulates ink along a route including

the return branch channel. If necessary, the controller 5 circulates ink along a route including the supply branch channel to remove bubbles accumulating in an upper portion of the filter F1. When ink circulates along the route including the return branch channel, ink in the subtank passes through the channel 11m in the tube 11a and is supplied to the supply channel 31 (see FIG. 4) through the opening 21a (see FIG. 5). Ink supplied to the supply channel 31 flows into the supply common channel 31e through the supply holes 31ex (see FIG. 3), passes through each individual channel 33 and the return common channel 32e in that order, and flows into the channel 32d (see FIG. 4) through the return holes 32ex. Ink flowing into the channel 32d passes through the channel 32d along the lower surface of the filter F2, passes through the return branch channel to outflow through the opening 21d (see FIG. 5), passes through the channel 11m in the tube 11d, and returns to the subtank. When ink circulates along the route including the supply branch channel, ink in the subtank passes through the channel 11m in the tube 11a and is supplied to the channels 31a and 31b of the supply channel 31 (see FIG. 4) positioned above the filter F1 through the opening 21a (see FIG. 5). Ink supplied to the channels 31a and 31b passes through the channel 31b along an upper surface of the filter F1, passes through the supply branch channel to outflow through the opening 21b (see FIG. 5), passes through the channel 11m in the tube 11b, and returns to the subtank.

In this embodiment, the head 1 corresponds to a liquid discharge head of the present disclosure, the channels 11m and channels 12 correspond to a first channel of the present disclosure, and the channels 31 to 33 correspond to a second channel of the present disclosure. The lower surface 10b corresponds to a first joining surface of the present disclosure, the upper surface 10a corresponds to an opposite surface of the present disclosure, the upper surface 20a corresponds to a second joining surface of the present disclosure, the openings 12x correspond to a first opening of the present disclosure, the openings 21c correspond to a second opening of the present disclosure, the wall 10w corresponds to a first wall of the present disclosure, and the wall 20w corresponds to a second wall of the present disclosure. The walls 14x correspond to a first extending portion, a second extending portion, and a third extending portion of the present disclosure, the walls 14y correspond to the second extending portion and a fourth extending portion of the present disclosure, the walls 16x correspond to the first extending portion, the second extending portion, and the third extending portion of the present disclosure, and the walls 16y correspond to the second extending portion and the fourth extending portion of the present disclosure. The COF 50 corresponds to a trace member of the present disclosure, the driver IC 60 corresponds to a driver of the present disclosure, and the heatsink 70 corresponds to a heatsink of the present disclosure. The vertical direction corresponds to an orthogonal direction of the present disclosure, the sheet width direction corresponds to a first direction and a fifth direction of the present disclosure, the conveyance direction corresponds to a second direction, a sixth direction, and a seventh direction of the present disclosure, and one of the sheet width direction and the conveyance direction corresponds to a third direction of the present disclosure, and the other corresponds to a fourth direction of the present disclosure.

Effects of Embodiment

In the first channel unit 10 of this embodiment, the upper ends in the vertical direction of the outside portion 14 and

the coupling portion 16 have the same height. The tubes 11 have the circumferential portions 11z that are exposed to the outside and have the same height in the vertical direction as the upper ends of the outside portion 14 and the coupling portion 16 (see FIG. 2). In that configuration, it is possible to apply pressing force to the circumferential portions 11z of the tubes 11, the outside portion 14, and the coupling portion 16 when the first channel unit 10 is joined to the second channel unit 20. This inhibits the joining failure between the first channel unit 10 and the second channel unit 20.

The outside portion 14 and the coupling portion 16 overlap in the vertical direction with the wall 20w (see FIGS. 5 to 7). In that configuration, pressing force applied to the outside portion 14 and the coupling portion 16 is directly transmitted to the wall 20w, thus improving the joining strength.

The openings 21c extend in the sheet width direction (see FIG. 5). The outside portion 14 includes the walls 14x extending in the sheet width direction, and the coupling portion 16 includes the walls 16x extending in the sheet width direction (see FIG. 6). The walls 14x and walls 16x do not overlap in the vertical direction with the openings 21c (see FIG. 7). In a case that the pressing force is applied to the openings 21c, a width (the length in the conveyance direction) of the openings 21c can be narrow. In this embodiment, however, pressing force is not likely to be applied to the openings 21c, thus inhibiting the openings 21c from narrowing.

The openings 12x and openings 21c extend in the sheet width direction. The length L2 in the conveyance direction of the portion included in the wall 20w and positioned between the openings 21c in the conveyance direction is longer than the length L1 in the conveyance direction of the portion (the lower end of each of the three walls 16x) included in the wall 10w and positioned between the openings 12x in the conveyance direction (see FIG. 7). When the first channel unit 10 is joined to the second channel unit 20 by applying pressing force to the circumferential portions 11z of the tubes 11, the outside portion 14, and the coupling portion 16, it is only required that the length L1 be a length capable of transmitting pressing force from the wall 10w to the wall 20w. The length L1 is thus not required to be too long. If the length L2 is too short, each channel 32a would not be formed appropriately, which easily causes ink leakage. In the configuration of this embodiment, however, the length L2 is longer than the length L1. This inhibits the length L2 from being too short, inhibiting ink leakage.

The center-to-center distance D in the conveyance direction between the four openings 12x is the same as the center-to-center distance D in the conveyance direction between the four openings 21c (see FIG. 7). This allows the openings 12x to reliably overlap in the vertical direction with the openings 21c, thus allowing the channels 12 to reliably communicate with the channels 32a.

The length (height) in the vertical direction of the walls 14x and walls 16x is longer than the length (thickness) in the conveyance direction thereof. The length (height) in the vertical direction of the walls 14y and walls 16y is longer than the length (thickness) in the sheet width direction thereof (see FIG. 2). Making the height of walls larger than the thickness thereof inhibits a warp of walls which may otherwise be caused when pressurization or heating is performed on the first channel unit 10 and the second channel unit 20 to be joined to each other. Specifically, the walls 14x and walls 16x are not likely to be deformed in the conveyance direction and the walls 14y and walls 16y are not likely

11

to be deformed in the sheet width direction. This inhibits a warp as well as the joining failure between the units **10** and **20**.

The outside portion **14** and the coupling portion **16** respectively have the walls **14x** and the walls **16x** extending in the sheet width direction, which is a longitudinal direction of the first channel unit **10** (see FIG. 6). In that case, the walls **14x** and walls **16x** are easily formed by flowing a resin in the sheet width direction in the injection molding of the first channel unit **10**. The first channel unit **10** is long in the sheet width direction. Thus, if the warp in the sheet width direction of the walls **14x** and walls **16x** is large, the first channel unit **10** would warp entirely and greatly. When the walls **14x** and the walls **16x** are formed by flowing the resin in the sheet width direction, the walls **14x** and the walls **16x** are likely to warp in the conveyance direction, but are not likely to warp in the sheet width direction. This inhibits the first channel unit **10** from warping entirely and greatly.

The portions (the lower ends of the three walls **16x**) included in the wall **10w** and positioned between the openings **12x** in the conveyance direction each have the length **L1** in the conveyance direction (see FIG. 7). In that case, variation in the flow rate of resin at the three portions, which is caused when the resin flows in the sheet width direction to form the three portions, is lower than a case the three portions have mutually different lengths **L1** in the conveyance direction. This inhibits a weld line at each portion.

The three portions define the channels **12** (see FIG. 7). If the weld lines are formed at the portions defining the channels, the channels would not be formed appropriately. This may cause ink leakage, and the like. The configuration of this embodiment inhibits such a problem.

The outside portion **14** and the coupling portion **16** include not only the walls **14x** and the walls **16x** extending in the sheet width direction that is the longitudinal direction of the first channel unit **10** but also the walls **14y** and the walls **16y** extending in the conveyance direction that is a lateral direction of the first channel unit **10**. In that case, providing the walls extending in the directions intersecting with each other improves the entire rigidity of the first channel unit **10**. Further, flowing the resin not only in the sheet width direction but also in the conveyance direction improves the fluidity of resin, which inhibits a void and sink mark. The void is a phenomenon in which air bubbles are caused inside a molded product, and the sink mark is a phenomenon in which a surface of the molded product is concave through contraction.

The wall **10w** has the recesses **19** (see FIG. 8). In that case, since the resin density of the wall **10w** is reduced, which inhibits the void and sink mark and improves the flatness of the lower surface **10b**. Further, excessive adhesive used for joining the units **10** and **20** can flow into the recesses **19**. This reliably inhibits the joining failure between the first channel unit **10** and the second channel unit **20**.

The recess(es) **19** is/are provided between the openings **11mx** (see FIG. 8). In that configuration, the recess(es) **19** is/are positioned in the vicinity of the openings **11mx**. Thus, the effect of enhancing the flatness provided by the recesses **19** reliably leads to the joining strength in the vicinity of the openings **11mx**.

The recesses **19** are separated from the openings **11mx** by not less than 0.5 mm. If the recesses **19** are too close to the openings **11mx**, a joining area (joining margin) around each opening **11mx** would be insufficient to join the units. This may cause the joining failure. In this embodiment, the recesses **19** are separated from the openings **11mx**, thus inhibiting such a problem.

12

The tubes **11** and the coupling portion **16** are arranged at each end in the sheet width direction of the first channel unit **10** (the longitudinal direction of the first channel unit **10**, see FIG. 6). When the unit is long in a certain direction, the joining failure is likely to be caused especially at the ends in the longitudinal direction of the unit. In the configuration of this embodiment, the tubes **11** and the coupling portion **16** are arranged at the ends in the sheet width direction, which is the longitudinal direction of the first channel unit **10**. The pressing force can thus be applied to the ends in the sheet width direction, which reliably inhibits the joining failure.

The tubes **11** and the coupling portion **16** are arranged (see FIG. 6) at the center portion in the sheet width direction of the first channel unit **10** (the longitudinal direction of the first channel unit **10**). When the unit is long in a certain direction, the joining failure is likely to be caused especially at the ends in the longitudinal direction of the unit. Further, since the unit easily curves in the longitudinal direction, the joining failure is likely to be caused also at the center portion in the longitudinal direction of the unit. In the configuration of this embodiment, the tubes **11** and the coupling portion **16** are arranged at the center portion in the sheet width direction, which is the longitudinal direction of the first channel unit **10**. The pressing force can thus be applied to the center portion, which reliably inhibits the joining failure.

A total of 16 tubes **11** are arranged symmetrically with respect to the center point **O** of the first channel unit **10** in the plane orthogonal to the vertical direction (see FIG. 6). In that configuration, pressing force can be applied symmetrically to the center point **O** via the tubes **11**, thus uniformly joining the first channel unit **10** to the second channel unit **20**.

Each individual channel **33** includes the inlet **33x** communicating with the supply channel **31** and the outlet **33y** communicating with the return channel **32** (see FIG. 4). In that configuration, ink circulates through each individual channel **33** ranging from the inlet **33x** to the outlet **33y** (a route including, for example, the pressure chamber **33c** positioned immediately above the nozzle **33d**). That configuration, however, requires many channels. Thus, if the head **1** is small, the joining area would be insufficient to join the units. This may easily cause the joining failure. In this embodiment, in order to solve the above problem, pressure force is applied to the circumferential portions **11z** of the tubes **11**, the outside portion **14**, and the coupling portion **16** to effectively inhibit the joining failure.

The outside portion **14** is provided with the driver IC **60** and the heatsink **70** (see FIG. 7). In the configuration, the driver IC **60** and the heatsink **70** are arranged by utilizing the outside portion **14** extending in the vertical direction.

The outside surfaces of the walls **14x** of the outside portion **14** have the hollows **14t** for guiding the COF **50** (see FIGS. 6 and 7). In the configuration of this embodiment, the COF **50** can be held appropriately by being guided by the hollows **14t**.

Of the four corners **14p1** to **14p4** of the outside portion **14**, the corner **14p1** is different in shape from the remaining corners **14p2** to **14p4** (see FIG. 6). In that configuration, the first channel unit **10** can be disposed at a correct position in joining of the units, thus inhibiting the deterioration in yield which may otherwise be caused when the first channel unit **10** is disposed at an incorrect position.

The positioning holes **1P** and positioning holes **1Q** overlapping with each other in the vertical direction are formed at the ends in the sheet width direction of the first channel unit **10** and the second channel unit **20** (the longitudinal direction of the units **10** and **20**, see FIGS. 5 and 6). In that

configuration, the long units **10** and **20** can be appropriately positioned relative to each other and then joined to each other.

Modified Embodiment

The embodiment of the present disclosure is explained above. The present disclosure, however, is not limited to the above. Various changes or modifications in the design may be made without departing from the claims.

In the present disclosure, the wording "the same" includes a case having a slight difference provided that the effect of the present disclosure is obtained.

In the above embodiment, the first channel unit and the second channel unit are made using a resin. However, the units may be made using any other appropriate material (e.g., a metal material) than the resin. Or, the material of the first channel unit may be different from that of the second channel unit.

The tube may not include the protrusion. Namely, the end in the orthogonal direction of the tube, the end in the orthogonal direction of the outside portion, and the end in the orthogonal direction of the coupling portion may have the same height. The tubes may not be arranged symmetrically with respect to the center point of the first channel unit. The number of tubes is not especially limited, and only one tube may be provided.

In the above embodiment, the outside portion has a circular shape. The present disclosure, however, is not limited thereto. For example, part of an outer circumferential portion of the first channel unit may not be provided with the outside portion so that part of the tube is disposed at the outermost position.

In the above embodiment, the coupling portion may extend, for example, in a direction parallel to the lower surface **10b** and intersecting with the sheet width direction and the conveyance direction.

In the above embodiment (see FIG. 7), the length **L2** may be identical to or shorter than the length **L1**. The center-to-center distance **D** between the openings **12x** may not be the same as the center-to-center distance **D** between the openings **21c**. The present disclosure is not limited to the configuration in which the center-to-center distance **D** between the openings **12x** is constant and the configuration in which the center-to-center distance **D** between the openings **21c** is constant. Three or more openings **12x** may be provided at different spaced intervals in the conveyance direction, and three or more openings **21c** may be provided at different spaced intervals in the conveyance direction.

The first wall (e.g., the wall **10w** of the above embodiment, see FIG. 8) may have no recesses (e.g., the recesses **19** of the above embodiment, see FIG. 8) between multiple first openings. The recess(es) may be provided only outside the first openings. The first wall may have no recesses.

Instead of providing multiple supply common channels and multiple return common channels, only one supply common channel and only one return common channel may be provided. For example, a channel unit **20z1** according to a first modified embodiment depicted in FIG. 9A includes a supply common channel **131e** and a return common channel **132e**.

The positions of the supply holes and the return holes and the number of the supply holes and the return holes are not limited to those of the above embodiment. For example, in the first modified embodiment depicted in FIG. 9A, a supply hole **131x** is provided at a first end in an extending direction of the supply common channel **131e** and a return hole **132x**

is provided a second end in an extending direction of the return common channel **132e**. In that configuration, the ink flow direction of the supply common channel **131e** is opposite to that of the return common channel **132e**.

5 The number of nozzles and pressure chambers included in each individual channel is not limited to those of the above embodiment. For example, in the first modified embodiment depicted in FIG. 9A, each individual channel **133** includes a nozzle **133d** and two pressure chambers **133c**. Each individual channel **133** may include two or more nozzles.

10 Each individual channel may not include the inlet communicating with the supply channel and the outlet communicating with the return channel.

15 For example, a channel unit **20z2** according to a second modified embodiment depicted in FIG. 9B includes one common channel **230**. The common channel **230** has a U shape when seen in the vertical direction. A supply hole **231x** is provided at a first end of the common channel **230** and a return hole **232x** is provided at a second end of the common channel **230**. Part included in the first end of the common channel **230** and not overlapping in the vertical direction with multiple individual channel **233** corresponds to a supply channel **231**. Part included in the second end of the common channel **230** and not overlapping in the vertical direction with the individual channels **233** corresponds to a return channel **232**. In the second modified embodiment, although each individual channel **233** communicates with the supply channel **231** and the return channel **232** via the common channel **230**, each individual channel **233** includes no inlet communicating with the supply channel **231** and no outlet communicating with the return channel **232**.

20 For example, a channel unit **20z3** according to a third modified embodiment depicted in FIG. 9C includes a common channel **330**. The common channel **330** has an I shape when seen in the vertical direction. A supply hole **331x** is provided at a first end of the common channel **330** and a return hole **332x** is provided at a second end of the common channel **330**. Part included in the first end of the common channel **330** and not overlapping in the vertical direction with multiple individual channels **333** corresponds to a supply channel **331**. Part included in the second end of the common channel **330** and not overlapping in the vertical direction with the individual channels **333** corresponds to a return channel **332**. In this modified embodiment, although each individual channel **333** communicates with the supply channel **331** and the return channel **332** via the common channel **330**, each individual channel **333** includes no inlet communicating with the supply channel **331** and no outlet communicating with the return channel **332**.

25 In the above embodiment, each of the supply channel and the return channel includes the branch channel. Bubbles in the head can be efficiently discharged through the branch channel. The present disclosure, however, is not limited thereto. For example, the configuration of the above embodiment may not include the supply branch channel, the tubes **11b**, the return branch channel, and the tubes **11d**.

30 The return channel may be omitted. Namely, instead of the configuration in which ink circulates between a tank and the head, only a channel for supplying liquid such as the ink from the tank to the head may be provided.

35 The actuator is not limited to a piezo-type actuator using piezoelectric elements. The actuator may be, for example, a thermal-type actuator using heating elements or an electrostatic-type actuator using electrostatic force.

15

The driver and the heatsink may be provided, for example, on the walls 14y of the outside portion 14 of the above embodiment. In that configuration, the walls 14y may include the hollows 14t.

The head is not limited to the line-type head. The head may be a serial-type head in which liquid is discharged from nozzles on a medium (an object to which liquid is to be discharged) during movement of the head in a scanning direction parallel to a sheet with direction.

The medium is not limited to the sheet or paper, and may be a cloth, a substrate, and the like.

The liquid discharged from the nozzles is not limited to the ink, and may be any liquid (e.g., a treatment liquid that agglutinates or precipitates constituents of ink, liquefied metal, and liquefied resin).

The present disclosure is applicable to facsimiles, copy machines, multifunction peripherals, and the like without limited to printers. The present disclosure is also applicable to a liquid discharge apparatus used for any other application than the image recording (e.g., a liquid discharge apparatus that forms an electroconductive pattern by discharging an electroconductive liquid on a substrate).

What is claimed is:

1. A liquid discharge head, comprising:
a first channel unit in which a first channel is defined, the first channel unit including:
a first joining surface;
an opposite surface that is opposite to the first joining surface;
a tube disposed on the opposite surface and defining the first channel;
an outside portion disposed on the opposite surface and positioned outside the tube, the outside portion having an end at an upper end of the first channel unit in an orthogonal direction orthogonal to the first joining surface; and
a coupling portion disposed on the opposite surface and coupling the outside portion and the tube, the coupling portion having an end at the upper end of the first channel unit in the orthogonal direction, and
a second channel unit in which a second channel communicating with the first channel is defined, the second channel unit including a second joining surface joined to the first joining surface of the first channel unit, wherein the end of the outside portion and the end of the coupling portion extend to an identical position in the orthogonal direction, and
the tube includes a circumferential portion that is exposed outside and extends in the orthogonal direction to the identical position to which the end of the outside portion and the end of the coupling portion extend.
  2. The liquid discharge head according to claim 1, wherein the first joining surface has a first opening for the first channel and a first wall defining the first opening, the second joining surface has a second opening for the second channel that overlaps in the orthogonal direction with the first opening, and a second wall defining the second opening, the first opening and the second opening extend in a first direction parallel to the second joining surface, and, the second wall is longer in a second direction than the first wall, the second direction being orthogonal to the orthogonal direction and the first direction.
  3. The liquid discharge head according to claim 2, wherein the first opening includes a plurality of first openings and the second opening includes a plurality of second openings, and
  - 16
- a center-to-center distance in the second direction between the first openings is the same as a center-to-center distance in the second direction between the second openings.
4. The liquid discharge head according to claim 1, wherein the second joining surface has a second opening for the second channel and a second wall defining the second opening, and
one of the outside portion and the coupling portion overlaps in the orthogonal direction with the second wall.
  5. The liquid discharge head according to claim 4, wherein the second opening extends in a first direction parallel to the second joining surface,
one of the outside portion and the coupling portion includes a first extending portion extending in the first direction, and
the first extending portion does not overlap in the orthogonal direction with the second opening.
  - 15
  6. The liquid discharge head according to claim 1, wherein one of the outside portion and the coupling portion includes a second extending portion extending in a third direction parallel to the opposite surface, and
a length in the orthogonal direction of the second extending portion is longer than a length in a fourth direction, which is orthogonal to the orthogonal direction and the third direction, of the second extending portion.
  - 20
  7. The liquid discharge head according to claim 1, wherein the first channel unit is made using a resin and is long in a fifth direction parallel to the first joining surface, and
one of the outside portion and the coupling portion includes a third extending portion extending in the fifth direction.
  - 30
  8. The liquid discharge head according to claim 7, wherein the third extending portion includes a plurality of third extending portions, and
the third extending portions have an identical length in a sixth direction that is parallel to the first joining surface and is orthogonal to the fifth direction.
  - 35
  9. The liquid discharge head according to claim 8, wherein the third extending portions define the first channel.
  10. The liquid discharge head according to claim 7, wherein one of the outside portion and the coupling portion includes a fourth extending portion extending in a seventh direction that is parallel to the first joining surface and intersects with the fifth direction.
  - 40
  11. The liquid discharge head according to claim 7, wherein the first joining surface has a first opening for the first channel and a first wall defining the first opening, and
the first wall includes a recess.
  12. The liquid discharge head according to claim 11, wherein the first opening includes a plurality of first openings, and the recess is located between the first openings.
  - 50
  13. The liquid discharge head according to claim 11, wherein the recess is positioned away from the first opening by not less than 0.5 mm.
  - 55
  14. The liquid discharge head according to claim 1, wherein the first channel unit extends in a fifth direction parallel to the first joining surface, and
the tube and the coupling portion are disposed at ends in the fifth direction of the first channel unit.
  15. The liquid discharge head according to claim 14, wherein the tube and the coupling portion are disposed at a center portion in the fifth direction of the first channel unit.
  - 60
  16. The liquid discharge head according to claim 14, wherein the tube includes a plurality of tubes, and

17

the tubes are arranged symmetrically with respect to a center point of the first channel unit in a plane orthogonal to the orthogonal direction.

17. The liquid discharge head according to claim 1, wherein the second channel includes a plurality of individual channels including a plurality of nozzles corresponding thereto, a supply channel, and a return channel, each of the individual channels has an inlet communicating with the supply channel and an outlet communicating with the return channel, and the first channel includes a channel communicating with the supply channel and a channel communicating with the return channel.

18. The liquid discharge head according to claim 1, further comprising: an actuator; a driver installed in the outside portion and configured to supply a driving signal to the actuator; and a heatsink thermally connected to the driver and installed in the outside portion to cover the driver.

19. The liquid discharge head according to claim 1, further comprising:

5

10

15

20

18

an actuator, and a trace member connected to the actuator and extending to an outside of the first channel unit, wherein a hollow configured to guide the trace member is located in an outside surface of the outside portion.

20. The liquid discharge head according to claim 1, wherein the outside portion includes a plurality of corners protruding toward the outside, and one of the corners is different in shape from the remaining other corners.

21. The liquid discharge head according to claim 1, wherein the first channel unit and the second channel unit extend in a fifth direction parallel to the first joining surface, and

each of the first channel unit and the second channel unit has positioning holes at ends in the fifth direction, the positioning holes of the first channel unit overlapping in the orthogonal direction with the positioning holes of the second channel unit.
